Primary Examiner — Shawn T Gingrich*Assistant Examiner* — Amanda Christensen(74) *Attorney, Agent, or Firm* — Scully, Scott, Murphy & Presser, P.C.(57) **CLAIM**

The ornamental design for a charging device, as shown and described.

DESCRIPTION

FIG. 1 is a front view of a charging device showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a right, front perspective view thereof; and,

FIG. 8 is a left, rear perspective view thereof.

The broken lines depict portions of the charging device that form no part of the claimed design.
